(74) Attorney, Agent, or Firm—Foley & Lardner

(57) **CLAIM**

The ornamental design for a work surface, as shown and described.

DESCRIPTION

FIG. 1 is a top front perspective view of a work surface showing my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a top front perspective view thereof with the environmental structure adjusted for clarity;

FIG. 9 is a left side elevation view of FIG. 8;

FIG. 10 is a right side elevation view of FIG. 8;

FIG. 11 is a rear elevation view of FIG. 8;

FIG. 12 is a front elevation view of FIG. 8;

FIG. 13 is a top plan view of FIG. 8; and,

FIG. 14 is a top front perspective view thereof with additional environmental structure.

The ornamental design which is claimed is shown in solid lines in the drawings. The broken lines in the drawings are for illustrative purposes only and form no part of the claimed design.
